UNITED STATES PATENT OFFICE.

ROBERT O. KING, OF BUFFALO, NEW YORK.

DESIGN FOR A ROCK-LEVER.

41,329.

Specification for Design.

Patented Apr. 25, 1911.

Application filed February 11, 1911. Serial No. 608,134. Term of patent 14 years.

To all whom it may concern:

Be it known that I, ROBERT O. KING, a citizen of Canada, residing at Buffalo, in the county of Erie and State of New York, have invented a new, original, and ornamental Design for Rock-Levers, of which the following is a specification, reference being had to the accompanying drawings, forming part thereof.

Figure 1 is a side elevation of a rock lever showing my new design. Fig. 2 is a top plan

view thereof. Fig. 3 is an elevation of the same viewed from the rear end thereof. Fig. 4 is an elevation of the same viewed from the front end thereof.

I claim:

The ornamental design for a rock lever, as shown.

ROBERT O. KING.
